UNITED STATES PATENT OFFICE

JAMES A. STRUTHERS, OF MINNEAPOLIS, MINNESOTA

DESIGN FOR HOSIERY OR THE LIKE

Application filed December 9, 1931. Serial No. 42,009. Term of patent 14 years.

To all whom it may concern:

Be it known that I, JAMES A. STRUTHERS, a citizen of the United States, residing at Minneapolis, in the county of Hennepin and State of Minnesota, have invented a new, original, and ornamental Design for Hosiery or the like, of which the following is a specification, reference being had to the accompanying drawing, forming part thereof, wherein the figure is a side view of a stocking showing my new design. The opposite side of the stocking is identical in appearance with the side illustrated.

What I claim is:

The ornamental design for hosiery or the like, substantially as shown and described.

JAMES A. STRUTHERS.
